TO Z. H. AUSTIN, TRUSTEE, OF MINNEAPOLIS, MINNESOTA.

INTERNAL-COMBUSTION ENGINE.

1,310,301.

Specification of Letters Patent. Patented July 15, 1919.

Application filed February 8, 1917. Serial No. 147,856.

To all whom it may concern:

Be it known that we, HARRY E. SHERMAN and CHESTER E. SHERMAN, citizens of the United States, residing at Anoka, in the 5 county of Anoka and State of Minnesota, have invented certain new and useful Improvements in Internal-Combustion Engines, of which the following is a specification.

Our invention relates to internal combustion engines and has for its object to provide a special firing chamber at the head of the cylinder in combination with a rotary sleeve valve so mounted that the same may readily be internally cooled, may be readily 10 oiled by novel means associated with the mounting, and will itself provide means for preventing leakage of gas from the firing chamber through the ports and around the valve. The firing chamber is preferably so 15 related with the cylinder of the engine that the rotary sleeve valve which is mounted concentrically to such chamber will also be concentric or in axial alinement with the cylinder.

In carrying out the objects of our invention we provide the valve and valve housing with complementary coöperating annular tongues and grooves whereby leakage of 20 gases along the bearing surfaces of the valve is entirely eliminated. The bearing for this valve is formed outside of the water-jacket, which encircles the firing chamber, so the valve rotates upon a bearing continuously 25 water cooled from within, and undue expansion of the valve is thus completely eliminated. An effective device for oiling the valve is provided by means of a groove in the valve casing which extends longitudinally of the valve, or along a cylindrical 30 element thereof, and which is supplied with the requisite amount of oil from suitable feeding means. This groove is at all times in contact with the outer surface of the valve, and as the ports in the valve come beneath 35 the same oil passes from the groove into said ports and is carried about and distributed on the inner bearing of the valve sleeve, thus simultaneously oiling both of the bearing surfaces.

The full objects and advantages of our invention will appear in connection with the detailed description thereof and are particularly pointed out in the claims.

In the drawings, illustrating the application of our invention in one form,— 55

Figure 1 is a plan view of an internal combustion engine with our invention applied thereto showing the valve mechanism and some of the other parts in section. Fig. 2 is an end view of the cylinder drawn to a 60 larger scale with some of the parts shown in section. Fig. 3 is an enlarged sectional view on line 3—3 of Fig. 1.

In the drawings our invention is shown applied to a stationary four-cycle internal 65 combustion engine. A base 10 has secured to it a cylinder 11 and a pair of bearings 12 and 13 in which is journaled a crank shaft 14. A piston 15 slidable in cylinder 11 is connected to a pitman 16 which in turn is connected to the crank shaft 14 of the engine. Upon the extreme ends of this shaft are mounted fly wheels 17 which are constructed in the ordinary manner.

The valve mechanism of our invention is 75 constructed as follows. Upon the end of cylinder 11 is formed a hollow cylindrical extension 18 which has a smaller bore than the cylinder proper and is open at both ends to communicate with said cylinder chamber. 80 A water-jacket 19 surrounds the cylinder 11 and extends radially inward at 21 and about the extension 18 at 20, forming a continuous water-circulating space about both of said 85 portions of the engine. Upon the outer periphery of the water-jacket 20, which serves as a valve supporting member, is rotatably mounted a sleeve valve 22 which is held in place by means of a cylinder head 23 rigidly bolted to the end of extension 18. An annular casing 24 formed with a flange 25 covers the sleeve 22 and is rigidly bolted to the portion 21 of the water-jacket through the flange 25. To this casing is secured an exhaust pipe 26 and an intake pipe 27 which 90 communicate with the interior of the cylinder extension through openings 28 and 29 in said casing, and through ports 30 and 31 in extension 18 and the jacket 20. A passage-way or port 32 is formed in the sleeve member 22, which port may successively register with ports 30 and 31 to permit the burnt gases to discharge and to permit a fresh 95 charge of mixture to be drawn in.

Valve member 22 is constantly driven in 100 the direction indicated by the arrow in Fig.

2 as follows. A spur ring gear 34 is formed integral with the valve 22 at the outer end thereof. This gear meshes with another spur gear 35 mounted on the end of a shaft 36 which is positioned longitudinally of the engine and is journaled in bearings 37 and 38 attached to the exterior of cylinder 11 and the engine base 10. Upon the other end of shaft 36 is rigidly secured a bevel gear 39 which meshes with a bevel gear 40 fast on the crank shaft 14. The ratios of the various gears sets are such that sleeve valve 22 travels at just one-half the speed of the crank shaft 14.

15 The operation of the device is the same as that of any four-cycle engine. The chamber within extension 18 serves as an explosion chamber and the cylinder head or cap 23 is provided with a spark plug 33 extending into this chamber by means of which the explosive mixture is ignited. As the valve 22 is rotated port 32 successively brings the interior of the engine cylinder in communication with the exhaust pipe 26 and the intake pipe 27, while burnt gases are being expelled and a fresh charge of explosive mixture is drawn in. As said valve port travels around the imperforate portion of the valve-supporting member the communication of the cylinder with the exterior is cut off and the fresh charge is compressed and exploded.

In order to prevent leakage of the gases past the sleeve member 22 and into the open, the following devices are used. Upon the outer periphery of the valve-supporting member 20 and the sleeve 22 adjacent the ports 30, 31 and 32, passing through the same, are placed four packing rings 41. The 40 ends of sleeve 22 are formed with annular tongues 42 which fit into corresponding grooves 43 formed on the sides of the cylinder head 23 and the water-jacket portion 21. Similarly, the outer end of the valve housing 24 is formed with a tongue 44 which enters a corresponding groove 45 in the side of the ring gear 34 used in driving the valve, which serves the same purpose. In this manner the valve is rendered perfectly 45 tight without causing undue friction, as the greater part of the gases are held back by the packing rings 41, while any traces of the same which leak past said rings are prevented from escaping by the aforementioned 50 tongue grooves 42 and 43.

55 For the purpose of lubrication a tube 46 is employed which is connected with the under side of the housing 24 and with a suitable oil reservoir not shown in the drawings. A longitudinal groove 47 shown in dotted lines in Fig. 1 is cut along the bottom of housing 24 into the bearing surface of the same and extends for a distance substantially equal to the length of the valve 60 member 22. When the valve is in operation

the outer periphery of the same is continuously oiled directly through this groove, while the inner periphery of the same is oiled by means of the port 32, which causes a charge of lubricating oil to be pocketed 70 within the same and to be distributed along the surface of contact of said sleeve and the member 20. By properly throttling the flow of lubricant in tube 46 the charge taken in port 32 can be regulated so that the same 75 is completely distributed when the valve has moved to cause said port to register with port 30.

80 The advantages of our invention are apparent. The engine is extremely simple in construction and is very efficient in operation, due to the reduction of friction gained by our improved oiling system, and due to the prevention of leakage of the gases within the cylinder.

85 We claim:

1. An internal combustion engine comprising an explosion cylinder having a firing chamber extending concentrically from the end of said cylinder, a cap closing the outer end of said cylinder, a water-jacket surrounding the cylinder and the firing chamber and being formed with an inner bearing surface, said firing chamber and water-jacket being provided with an exhaust port 90 and an inlet port, an outer casing, a sleeve valve mounted for rotation upon said bearing surface and within the casing, said sleeve valve having a suitably-positioned port 95 therein for coöperating with said exhaust port and said inlet port, annular tongues on the valve-entering grooves in said cylinder and cap, and means for continuously operating the sleeve valve in timed relation to the explosions of the engine. 100

105 2. An internal combustion engine comprising an explosion cylinder having a firing chamber extending concentrically from the end of said cylinder and having facing grooves adjacent the firing chamber, a water-jacket surrounding the cylinder and the firing chamber and being formed with an inner bearing surface, said firing chamber and water-jacket being provided with an exhaust port and an inlet port, a sleeve valve mounted for rotation upon said bearing surface and having a suitably-positioned port 110 therein for coöperating with said exhaust port and said inlet port, annular tongues on the ends of the sleeve valve extending into the facing grooves in said cylinder, and means for continuously operating the sleeve valve. 115

120 3. In an internal combustion engine an explosion cylinder, a cylindrical firing chamber, having an exhaust port and inlet port, extending outwardly from the end of the cylinder, a cap closing the end of the firing chamber and having an annular groove 125 therein and a sleeve valve rotatably mount- 130

ed upon said firing chamber and having an annular tongue rotatable in the cap groove.

4. An internal combustion engine comprising an explosion cylinder and an attached cylindrical firing chamber, said explosion cylinder being provided with an annular groove adjacent the outer surface of the firing cylinder, a removable cap closing the other end of the firing cylinder and 5 provided with an annular groove facing the first-named groove, and a sleeve valve mounted for rotation upon the firing cylinder and having annular tongues on the ends thereof entering said annular grooves. 10
- 15 5. An internal combustion engine comprising an explosion cylinder and an attached cylindrical firing chamber, said explosion cylinder being provided with an annular groove adjacent the outer surface of 20 the firing cylinder, a removable cap closing the other end of the firing cylinder and provided with an annular groove facing the first-named groove, a sleeve valve mounted for rotation upon the firing cylinder and 25 having annular tongues on the ends thereof entering said annular grooves, and a cylindrical casing member surrounding said sleeve valve. 30
6. An internal combustion engine comprising an explosion cylinder and an attached cylindrical firing chamber, said explosion cylinder being provided with an annular groove adjacent the outer surface of the firing cylinder, a removable cap closing 35 the other end of the firing cylinder and provided with an annular groove facing the

first-named groove, a sleeve valve mounted for rotation upon the firing cylinder and having annular tongues on the ends thereof entering said annular grooves, a gear cast 40 integrally with said sleeve valve in proximity to said cap, and a casing surrounding the sleeve valve and formed with an annular tongue thereof projecting into a groove in the side of the spur gear. 45

7. An internal combustion engine comprising casing members surrounding a firing chamber and formed with an annular horizontally-positioned passageway between said members having bearing surfaces on 50 each side of said passageway, said casing members being formed with an exhaust port and an inlet port extending through the same, a horizontally-positioned sleeve valve 55 rotatably mounted within the annular passageway and having a port adapted to cooperate with said exhaust port and inlet port, and means including an oil supply pipe and a passageway in the outer casing extending along and open at its side to an 60 element of said sleeve valve for causing oil to be distributed directly to the outer bearing surface thereof and into the valve port and thereby to the inner bearing surface of the sleeve valve. 65

In testimony whereof we affix our signatures in the presence of two witnesses.
